(57) **CLAIM**

The ornamental design for a cylinder for dental implant, as shown and described.

DESCRIPTION

FIG. 1 is a perspective view of a cylinder for dental implant showing my new design;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a cross-sectional view that is taken along a line VIII-VIII of FIG. 6.
